FOREIGN PATENT DOCUMENTS

GB 2479216 A 10/2011

Primary Examiner — George D Kirschbaum*Assistant Examiner* — Natasha Vujcic(74) *Attorney, Agent, or Firm* — Lando & Anastasi, LLP;
John N. Anastasi; William J. Seymour(57) **CLAIM**

The ornamental design for a light fixture, as shown and described.

DESCRIPTION

FIG. 1 is a perspective view of a light fixture;

FIG. 2 is an end view of a light fixture;

FIG. 3 is a bottom view of a light fixture;

FIG. 4 is a top view of a light fixture;

FIG. 5 is a right side view of a light fixture; and,

FIG. 6 is a left side view of a light fixture.

The broken lines in the drawings illustrate portions of the light fixture which form no part of the claimed design.

The break lines in the drawings indicate that the appearance of any portion of the light fixture between the break lines forms no part of the claimed design.

1 Claim, 5 Drawing Sheets---
